UNITED STATES PATENT OFFICE.

ORLANDO R. ERWIN, OF FOREST HILLS, NEW YORK, AND WILLIS D. WITTER, OF ROSELLE PARK, NEW JERSEY, ASSIGNEES, BY MESNE ASSIGNMENTS, TO AMERICAN LA FRANCE AND FOAMITE CORPORATION, A CORPORATION OF NEW YORK.

FOAM-SYSTEM MIXER CONNECTER.

Application filed April 8, 1921. Serial No. 459,576.

This invention is an improved construction of hose connector and mixer for use on the duplex hose lines of foam fire extinguishing systems and its object is to provide a connecting and mixing device of small, compact form and extremely light in weight, so that it will not form a drag on the lines when they are being pulled along to the fire and while yet adequately strong to resist the rough usage to which such connectors are necessarily subject, while also providing for the production of the foam by the impingement method, that is to say by the impingement of a flow of one solution counter to the flow of the other solution within the interior of the connector device. Mixers heretofore used in foam hose lines have consisted of a simple Y-form connector in which impingement does not occur and the benefits of the impingement method have not been capable of convenient use in such connectors because of the relatively large size of the pot-like chamber in which the mixing is effected.

According to my invention the impingement method of mixing the solutions is effectively carried out in a device which is actually smaller than the non-impinging Y-form connectors above referred to, and which can accordingly be used with far greater convenience. The invention consists of a one-piece casting formed with a relatively large outlet or mixing chamber open in one direction and two adjacent inlet chambers open in the opposite direction and having communication with the outlet chamber respectively at opposite sides thereof, the longitudinal axes of all three chambers being parallel to each other and the maximum diameter of the outlet chamber being not substantially greater than the interior diameter of the coupling and foam-conducting hose to be connected thereto.

Figure 1 is a longitudinal cross section of the improved mixer-connector. Fig. 2 a top plan thereof. Fig. 3 a side elevation; and Fig. 4 represents its manner of use.

Referring first to Fig. 4, the mixer-connector, there marked 10, is shown intervening between the two solution hose lines 26 and 27 (combined in a single casing 28) and a short hose or pipe section 18 to which it is connected by a coupling nut 19. The hose lines 26 and 27 are respectively connected to pipes 29 and 30 constituting the supply source of

the two foam-making solutions. The short 55 hose section 18 terminates in a nozzle 20 and this section is preferably a short section, as stated, because the two solutions meet and produce the foam in the connector 10 and it is desirable that the foam there produced be 60 discharged immediately and be not required to pass through a long hose or pipe, which would tend to impair its quality. In consequence of this condition the connector 10 requires to be located within a few feet of the 65 discharge nozzle, being, in fact, a part of the delivery end of the duplex hose line. It is therefore desirable that such connector be as compact and as light as possible, so that it can be freely pulled about as the nozzle is 70 carried about by the fireman.

As shown in the other figures of the drawing, the new mixer-connector is a one-piece casting. The two inlet chambers 11 and 12 are parallel to each other and both open in 75 the same direction and both are disposed on opposite sides of the central mixing and outlet chamber 13 which latter chamber is parallel to the others but opens in the opposite direction. The two inlet chambers 11 and 80 12 are disposed as closely together as will permit manipulation of their respective coupler nuts 21 and 22 and the portions of their side walls which are marked 14 and 15 form parts of the side walls of the outlet chamber 85 13. The bottom of said outlet chamber 13 is trough-shaped in section, as indicated in Fig. 3 and the wall portions just referred to form the ends of the trough. The solution discharge ports 16 and 17 are formed in these 90 same wall portions, at the ends of the trough and so as to direct the solutions into impinging contact in the bottom of the trough. The trough shape of the outlet chamber merges into a cylindrical shape at its outer 95 end, just beyond the inlet chambers where it is about twice the diameter of either of said chambers. It is threaded (19') at this outer cylindrical end so that it may be coupled to the hose section 18, which section is also 100 about twice the diameter of the inlet chambers. It will be noted also that the outlet chamber opens directly and without restriction into the foam pipe 18, the interior diameter of which approximates that of the outlet 105 chamber; the outlet orifice of said chamber, where the threads 19 are located, is the largest diameter of said chamber.

By means of the foregoing construction the solutions are brought together to produce foam in the most efficient manner, i. e. by impingement, and in the smallest possible compass, so that the device is easily portable and constitutes the least obstruction and drag when pulled over the ground or a floor. It is, at the same time, easily formed as a casting and is very strong and entirely free of any likelihood of becoming deranged or injured in use. The inlet hose couplers 21 and 22 are flanged at 23 so that they are retained in the grooves 24 according to usual hose coupler design and they are also provided with washers 25.

The following is claimed as new:

In apparatus of the class described, a one-piece mixer connector comprising a central chamber having an elongated trough shaped

bottom, of a length approximately double its 20 width, a mouth flaring outwardly for connection to a hose and of a diameter equal to the major cross-sectional dimension of the trough, a solution inlet chamber, on each side of the central chamber, of a diameter substantially equal to the minor cross-sectional dimension of the trough, the side walls of the inlet chambers constituting the end walls of the trough, opposed openings in said end walls for producing impingement mixing of 30 the foam-making solutions and a hose coupling mounted on the inlet end of each of said inlet chambers.

Signed at New York, in the county of New York and State of New York, this 7th day 35 of April, A. D. 1921.
